UNITED STATES PATENT OFFICE.

AMON LESLIE STEWART, OF PORT ARTHUR, TEXAS.

RAIL-JOINT.

1,366,845.

Specification of Letters Patent. Patented Jan. 25, 1921.

Application filed August 15, 1918. Serial No. 250,039.

To all whom it may concern:

Be it known that I, AMON LESLIE STEWART, a citizen of the United States, residing at Port Arthur, in the county of Jefferson and State of Texas, have invented new and useful Improvements in Rail-Joints, of which the following is a specification.

This invention comprehends generally improvements in that class of inventions known 10 as railway rails and joints and more particularly has reference to an improved rail joint.

It is the principal aim and object of the present invention to provide a device of the above mentioned character wherein the meeting 15 ends of a pair of rail sections are designed for interlocking engagement while cooperating therewith is suitable fastening means for positively locking the parts against accidental displacement.

It is a more specific object of this invention to provide a device of the above mentioned character wherein the meeting ends 20 of the rail sections are designed to be locked in engagement with each other in such a manner as to permit of the expansion and 25 contraction thereof and at the same time obviate knocking when rolling stock passes over the joint.

It is an additional object of this invention to provide a device of the above mentioned character which is simple in construction, thoroughly reliable and efficient in its purpose and inexpensive in manufacture.

Other objects will be in part obvious and in part hereinafter set forth.

The invention accordingly consists in the features of construction, the combination of elements and the arrangement of parts 40 which will be amplified in the construction hereinafter described and the scope of the application of which will be indicated in the appended claim.

The invention is clearly illustrated in the 45 accompanying drawings, in which—

Figure 1 is a side elevation of the improved rail joint partly broken away and shown in longitudinal section.

Fig. 2 is a cross-sectional view of the device.

Fig. 3 is a perspective detail of one end of one of the rail sections, and

Fig. 4 is a perspective detail of the adjacent end of another rail section.

Similar characters of reference are employed in all of the above described views, to indicate corresponding parts.

Referring now, more particularly, to the accompanying drawings there is provided a pair of rail sections 1 and 2 the meeting 60 ends of which are connected together by means of an improved joint generally indicated by the numeral 3 designed for holding the rail sections 1 and 2 in abutting relation and in alinement with each other.

In reducing the present invention to practice the rail section 1 is provided with an enlarged web portion 4 while the head of the section 1 above the enlarged web is cut away leaving a shoulder 5. The web portion 70 4 is also provided with a pair of longitudinally arranged and vertically extending rectangular openings 6 the upper and lower ends of which respectively open at the upper surface of the enlarged web portion 4 and 75 the base of the rail section 1, as clearly indicated. In addition the web portion 4 is provided with spaced transverse bolt receiving openings 7 which intersect the openings 6. The adjacent end of the other rail 80 section 2 has a head extension 8 projecting longitudinally therefrom, the edges of the web and base portions of the section constituting a shoulder 9. Depending from the under surface of the head extension and integral therewith is a pair of longitudinally spaced lugs 10 desirably rectangular in cross-section and of width slightly less than the width of the opening 6. These lugs are provided with transversely arranged and 90 substantially oval-shaped openings 11 which are engaged by bolts 12 subsequent to the insertion of the lugs in the openings 6, the bolts 12, of course, being passed through the openings 7 preparatory to the engagement 95 of the openings 11 while the threaded extremities thereof are engaged by nuts 13 for the positive retaining of the rail sections 1 and 2 together. The oval openings 11 permit of the contraction and expansion of the 100 rail sections. The free edge of the head extension 8 abuts the shoulder 5 while the free edge of the base and web portion of the rail section 1 abuts the shoulder 9 at the time the lugs are engaged in the openings 6. 105

It is to be observed that the length of the lugs is substantially the same as the height of the openings 6 and the free edges of the

lugs lie flush with the base of the rail section 1 when the parts are engaged in the manner described. Inasmuch as the head extension 8 is supported on the enlarged web and lies in alignment and substantially flush with the head of the rail section 1 it is apparent that knocking is obviated when rolling stock passes over the joint.

It is believed in view of the foregoing description that a further detailed description of the operation of the invention is entirely unnecessary. Likewise it is believed that the advantages of the invention will be readily apparent.

As many changes could be made in the above construction and many apparently widely different embodiments of this invention could be made without departing from the scope thereof it is intended that all matter contained in the above description or shown in the accompanying drawings shall be interpreted as illustrative and not in a limited sense. It is also to be understood that the language used in the following claim is intended to cover all the generic and specific features of the invention herein described and all statements of the scope of the invention which as a matter of language might be said to fall therebetween.

What I claim is:

A rail joint comprising the meeting ends of two rail sections, the one being formed with an enlarged or thickened web portion, the said thickened web portion having vertically disposed rectangular openings formed therethrough and spaced from each other, the tread of said section terminating short of that opening the farther from the end of the section, the other section being formed with a head or tread extension resting on top of the enlarged web, the said head extension having depending from the under surface thereof a spaced pair of lugs of the same cross sectional outline as the said openings but of slightly reduced dimensions as respects the latter, the thickened web portion being formed with transverse openings intersecting the vertical openings and the lugs being formed with oval shaped openings whose major axes are disposed in the direction of the length of the rails, the transverse openings in the enlarged web portion and in the lugs being adapted for the reception of bolts to secure the two parts of the joint together.

In testimony whereof I affix my signature.

AMON LESLIE STEWART.
